PRESSING MACHINE

Otto H. Pearson and Edward Pearson, Salt Lake City, Utah, assignors, by mesne assignments, to Nicholas L. Strike, Salt Lake City, Utah

Application August 27, 1937, Serial No. 161,188

16 Claims. (Cl. 192—131)

Our invention relates to pressing machines, and more particularly to two-hand control pressing machines.

An important object of the invention is the provision in pneumatic means for operating such a machine, of a pilot valve, operable by relatively slight manual power, to actuate said pneumatic means.

In a machine of the character mentioned having three-position manuals for actuating the pilot valve, an object of the present invention is the elimination of spring means that moves the manuals from an intermediate to an inoperative position.

The invention also comprises novel details of construction and novel combinations and arrangements of parts, which will more fully appear in the course of the following description.

In the drawings, like reference characters designate similar parts in the several views.

Figure 1 is a side elevation of an embodiment of our invention.

Figure 2 is an enlarged section, taken on the line 2—2 of Figure 1.

Figure 3 is a reduced elevation, looking in the direction of the arrows 3—3 of Figure 2.

Figure 4 is an elevation, partly in section, taken on the line 4—4 of Figure 2.

Figure 5 is a reduced plan view, similar to Figure 2, but showing another position in the operation.

Figure 6 is an enlargement of a detail herein-after more fully described.

Figure 7 is a broken, enlarged section of pneumatic driving means comprised in the embodiment.

Figure 8 is a section through valve means for controlling the mechanism of the machine.

Referring more in detail to the drawings, the reference number 10 generally designates the frame of the present machine, which supports a relatively stationary buck 12 and a pivotally mounted head 13. An arm 14, which supports the head 13, is pivotally mounted on the frame at 15. The arm 14 is in turn pivotally connected with a link 16.

The link 16, together with a therewith pivotally connected link 17, form a toggle generally designated 18. The lower end of the link 17 has a pivotal connection with a piston rod 19. A roller bearing 20, on the knuckle formed by the links 17 and piston rod 19, rides on a cam 21 having an upwardly inclined face 22 and a concave top face 23. A spring 61 may be coiled about the piston rod 19, to cushion inward move-

ment of the rod 19 into its cylinder hereinafter described.

One end of an oscillating tie bar 25 is pivotally mounted on a spindle 26 on the frame. The other end is connected with an offset stub shaft 24 at the elbow of the toggle 18.

A cylinder 27 has a ball and socket connection 28 with the frame of the machine, to permit oscillation of the cylinder. A piston 29 in the cylinder is mounted on the piston rod 19.

Heavy coil springs 30 and 31 tend to move the head 13 to the open position shown in Figure 1. The link 16 carries an ear 32 for reciprocating movement of a rod 33. A stop 34 on the rod 33 provides an abutment opposed to the ear 32, between which a spring 35, coiled about the rod 33, is disposed. An auxiliary spring 36, connecting with the frame and with the stop 34, may also be used. The springs 35 and 36 tend to move the rod toward the front of the machine.

Another stop 37 is disposed on the rod 33 on the other side of the ear 32 from the stop 34. The stop 37 may be the form of a nut on a threaded portion of the rod 33, to permit adjustments of the stop 37. By this arrangement, movement of the ear 32 in one direction compresses the spring 35, tending to move the rod 33 forward, and movement of the ear 32 in the opposite direction causes it to strike the stop 37, effecting rearward movement of the rod.

A pipe 38 supplies air pressure, or other pressure fluid, to the machine. A manual valve 39 controls the flow therethrough. A branch 40 of the pipe 38 leads to a valve casing 41, herein-after more fully described. The pipe 38 connects with a valve housing 42.

The housing has chambers 43 and 44 connecting by means of a passage 45. A ball valve 46 in one position closes the passage 45. A coiled spring 47 tends to move the ball valve 46 to said passage closing position. To aid in assembling, the chamber 43 is closed by a screw plug 48. A pipe 49 connects the chamber 44 with a passage 50 in head 51 of the cylinder 27. The passage 50 directs pressure fluid into the cylinder against the face of the piston 29, to urge the piston to the right in Figure 7.

An exhaust 52 connects with a chamber 53 in the valve housing 42. The chambers 44 and 53 connect by means of a passage 54, the walls of which passage provide a valve seat.

A valve 55, having a relatively slender pin 56 integral therewith, is disposed to reciprocate in the housing 42. The valve 55 when depressed engages the seat in the passage 54. When so

5

30

35

40

45

50

55

depressed, the pin 56 pushes the ball valve 46 from its passage closing position, against the action of the coiled spring 47. Thus in said depressed position, the valve 55 closes the passage 54 and opens the passage 45, permitting fluid pressure to flow from the pipe 38, through the chamber 43, through the passage 45 through the chamber 44, and through the pipe 49 to the cylinder 27, to actuate the piston 29.

10 When the valve is released from said depressed position, the coiled spring 47 seats the ball valve 46 and through the intermediary of the pin 56 causes the valve 55 to move from its seat. In this position of the two valves, the flow of pressure fluid from the source to the cylinder is stopped, but since the chambers 44 and 53 are now connected, pressure fluid ahead of the piston 29 may pass through chamber 44, through passage 54, through chamber 53 and out at the exhaust 52.

15 A shell 57 has bolted between the complementary halves thereof, a diaphragm 58. A pin 59 fastened to the diaphragm reciprocates therewith. At the opposite side of the diaphragm from the pin 59, the shell 57 receives pressure fluid 20 from a pipe 60. It will be noted that the pin 59 is arranged to depress or actuate the valves 55 and 46 against the action of the spring 47.

The mechanism is actuated by a pair of spaced manuals 62 and 63. It is to be understood that 30 the manuals are so spaced that they cannot be operated by a single hand, but require both hands of the operator to operate. This arrangement prevents the operator from getting his or her hands caught between the descending head 13 and the buck 12, which would injure and burn the operator's hands.

A table 64 is shown under the buck, and a flange 65 depends from the table. Openings 66 and 67 are arranged in the flange 65 to reach 40 the ends only of the manuals 62 and 63 respectively.

The manuals 62 and 63 are pivoted at 68 and 69, which pivots are mounted upon a platform 70 beneath the table 64. A strap 71 ties the pivots 68 and 69 together. Mounted rigidly on the manuals 62 and 63 and forming bell cranks therewith are arms 72 and 73 respectively. Stops 74 and 75 limit outward movement of the arms 72 and 73. The bolts 100 rigidly fasten the arms 50 72, 73 to the manuals 62, 63 respectively. The bolts 100 are not pivots.

A whippetree 75 is fastened at its ends to the arms 72 and 73, by means of links 76 and 77 respectively. The whippetree, adjacent its mid-point, carries a head 78 which is pivotally connected to the whippetree. The head 78 has a cylindrical recess for a relatively stiff spring 79.

A finger 80 has a head 81 in the recess of the head member 78. The head member 78 itself 60 limits the outward movement of the finger head 81, and the inward movement of the finger is limited by the spring 79.

A valve 82 is mounted for reciprocation in the valve casing 41. A nut 84 on the valve 82 limits its inward movement of said valve relative to the casing 41. The nose of the valve 82 is elongated, as shown at 85, and engages a ball valve 86. A coiled spring 87 behind the ball valve 86 urges same against its seat in the casing 41. When 70 the valve 82 is moved inward relative to the casing 41, the ball valve 86 is moved from its seat against the action of the spring 87.

The valve casing 41 has a chamber 88 that is provided with exhausts 89. The pipe 60 connects with a chamber 90 in the casing 41. The

5 pipe 40 connects with a chamber 91 also in the casing 41. A pipe 92 is normally closed, but may be connected with valve control means (not shown) if the machine is connected in tandem with another machine.

The nose 85 of the valve 82 fits loosely in the casing, whereby fluid pressure may pass around same at all times. The chambers 88 and 90 and chambers 90 and 91 are connected by the passages in which the nose 85 loosely fits. A screw plug 10 93 closes the end of the casing 41 adjacent the spring 87.

When the spring 87 is seating the ball valve 86 upon its seat (which is its normal position when the manuals are in the full line positions shown 15 in Figure 2), the flow of pressure fluid from the source is stopped. Moreover, in this position the exhausts 89 are connected with the diaphragm shell 57, whereby the diaphragm may be moved by its spring 94 to the position shown in Figure 20 8, releasing the valve 55.

When the valve 82 is moved inward relative to the casing 41, the taper of the valve 82 seats and thus seals the passage between the chambers 88 and 90, thereby shutting off the exhausts. 25 At the same time the ball valve 86 is unseated, connecting the chambers 90 and 91 and thereby permitting fluid pressure to flow from the pipe 40 to the pipe 60, thus actuating the diaphragm 58, which in turn operates the main supply 30 valve 46. It will thus be seen that the valve 86 acts as a pilot valve, requiring only relatively slight pressure to operate the main valve 46 of the machine.

To temporarily limit movement of the arms 72 35 and 73 toward each other, a barrier 95 is provided. It is in the shape of a bell crank 96 pivoted at 97. The rod 33 connects with the lower end of the bell crank 96, to move the barrier 95 to and from a position between the arms 72 and 73. The barrier is beveled, to force the arms 72 and 73 apart (from the position shown 40 in Figure 5) when the barrier is moved between them. The arms 72 and 73 have a limited movement between the stops 74 and 75 and the barrier. A stop 99 limits inward movement of the arms 72, 73, when the barrier is removed.

To initiate the operation of the present invention, both manuals 62, 63 and must be moved from the full line to the broken line positions 50 shown in Figure 2. If only one manual is so moved, the whippetree 75 is turned upon the head 78 without moving said head.

When both manuals are moved to the broken line positions, the head 78 is advanced to the 55 right in Figure 2. This movement causes the finger 80 to actuate the valve 82, which opens the pilot valve 86 in the manner described hereinbefore. The pressure fluid then actuates the diaphragm, which opens the main valve 46 as explained hereinbefore. Fluid pressure is thereby admitted to the cylinder 27, thus driving the piston 29.

The force against the piston moves the roller bearing 20 up the inclined face 22 and then 60 around the concave face 23. This movement causes the closing of the head 13 down upon the buck 12, as shown in broken lines in Figure 1, against the action of the springs 30, 31.

During the foregoing operation, the arms 72, 70 73 are against the sides of the barrier 95. If, prior to the time the head 13 engages or substantially engages the buck 12, the operator releases either hand, the whippetree is turned, or if both hands are released, the force upon the whippetree is 75

released. In either event, there is nothing to maintain the pilot valve 86 off its seat. When said valve is seated, the flow of fluid pressure is checked, releasing the main valve 46 and permitting same to be seated, which checks the pressure flow to the cylinder 27. Since the cylinder is then connected with the exhaust 52, the large coil springs 30, 31 may and do return the head to the open, full line position shown in Figure 1.

By the time the head 13 engages or substantially engages the buck 12, the ear 32 has engaged the nut 37, thus drawing the rod 33, which withdraws the barrier from between the arms 72.

15 73. The operator may then move the manuals to the locked position shown in Figure 5. The locked position is the over-center or past center position of the arms 72, 73 and the links 76, 77, which arms and links respectively form opposed toggles. In this position, the operator may release both manuals and the head 13 will remain in pressing engagement with the buck 12.

To raise the head 13, all that is necessary is to release either manual or both manuals. The 25 manuals float in the inoperative or rest position designated by the full lines in Figure 1. This machine is marked by the absence of spring means to maintain the manuals in the full operative position (Figure 5), and by the absence of 30 spring means that move the manuals from the intermediate (broken line position in Figure 1) to the inoperative position. The springs 79 and 87 are only to compensate for wear of the valves 82 and 86 and their respective seats and are 35 not adapted nor intended to perform the functions mentioned earlier in this paragraph, there being too little "stretch" or extent in such springs. Moreover, these springs are strong springs and are compressed to a relatively slight 40 extent in the operation of the machine.

Upon release of either manual or both manuals, the fluid pressure is cut off, the pressure in the cylinder is exhausted, allowing the springs 30, 31 to raise the pressing head 13. At the same 45 time the ear 32 moves away from the stop 37, thus releasing the rod 33 and allowing the springs 35, 36 to move the barrier up between the arms 72, 73.

It will be seen that the operation is in two 50 steps: (a) The manuals are movable from the full line, inoperative position of Figure 2 to the broken line, intermediate position of the same figure; and (b) the manuals are movable from said broken line, intermediate position, to the 55 full operative position shown in Figure 5. The first step lowers the head 13 into contact with the buck 12 and the second step locks the manuals with the head in such contacting position.

While we have illustrated and described what 60 we now regard as the preferred embodiment of our invention, the construction is, of course, subject to modifications without departing from the spirit of our invention. We, therefore, do not wish to restrict ourselves to the particular form 65 of construction illustrated and described, but desire to avail ourselves of all modifications which may fall within the scope of the appended claims.

Having thus described our invention, what we 70 claim and desire to secure by Letters Patent is:

1. A pressing machine comprising head and bed members, at least one of which is movable, operating mechanism for the movable member, and control means for said mechanism, including spaced manuals movable from inoperative

to intermediate positions and thereafter to full operative positions, means to lock the manuals in full operative positions, means governed by the relative positions of the head and bed members controlling movement of the manuals from intermediate to full operative positions, a source of pressure fluid connected with said operating mechanism, a valve controlling the entire flow of said pressure fluid to said mechanism, means controlling said valve, and mechanism operable by pressure fluid from said source arranged to actuate the last mentioned means when the manuals are in the intermediate or full operative positions.

2. A pressing machine comprising head and bed members, at least one of which is movable, operating mechanism for the movable member, and control means for said mechanism, including spaced manuals movable from inoperative to intermediate positions and thereafter to full operative positions, means to lock the manuals in full operative positions, means governed by the relative positions of the head and bed members controlling movement of the manuals from intermediate to full operative positions, a source of pressure fluid connected with said operating mechanism, valve means controlling the entire flow of said pressure fluid to said mechanism, fluid actuated means controlling said valve means, conduit means to convey pressure fluid to said fluid actuated means, and valve means controlling the flow through said conduit means and operable by the manuals when same are in the intermediate or full operative positions.

3. A pressing machine comprising head and bed members, at least one of which is movable, operating mechanism for the movable member, and control means for said mechanism, including spaced manuals movable from inoperative to intermediate positions and thereafter to full operative positions, means to lock the manuals in full operative positions, means governed by the relative positions of the head and bed members controlling movement of the manuals from intermediate to full operative positions, a source of pressure fluid connected with said operating mechanism, valve means controlling the entire flow of said pressure fluid to said mechanism, a diaphragm controlling said valve means, conduit means to convey pressure fluid to said diaphragm, and valve means controlling the flow through said conduit means and operable by the manuals when same are in the intermediate or full operative positions.

4. A pressing machine comprising head and bed members, at least one of which is movable, a fluid motor arranged to operate the movable member, and control means for the fluid motor, including spaced manuals movable from inoperative to intermediate positions and thereafter to full operative positions, means to lock the manuals in full operative positions, means governed by the relative positions of the head and bed members controlling movement of the manuals from intermediate to full operative positions, main valve means connected to control the entire motive fluid to the motor, and a pilot valve connected to operate the main valve means, the pilot valve operable by the manuals when same are in the intermediate or full operative positions.

5. A pressing machine comprising head and bed members, at least one of which is movable, a fluid motor arranged to operate the movable member, and control means for the fluid motor, including spaced manuals movable from inoperative

ative to intermediate positions and thereafter to full operative positions, means to lock the manuals in full operative positions, means governed by the relative positions of the head and bed members controlling movement of the manuals from intermediate to full operative positions, a main valve connected to control motive fluid to the motor, and arranged to move with the flow of the motive fluid when moving to a closed position, and a pilot valve arranged to move with the flow of the motive fluid when moving to a closed position, the pilot valve being connected to maintain the main valve in an open position when the manuals are in the intermediate or full operative positions, the pilot valve and main valve being movable to closed positions when the manuals are moved to inoperative positions.

6. A pressing machine comprising head and bed members, at least one of which is movable, operating mechanism for the movable member, and control means for said mechanism, including spaced manuals movable from inoperative to intermediate positions and thereafter to full operative positions, a whipple-tree connected to be moved to a position in which said control means is actuated, over-center toggles respectively connecting the manuals with the whipple-tree, the toggles being at one side of dead center when the manuals are in inoperative or intermediate positions and being locked at the opposite side of dead center when the manuals are in full operative positions, means governed by the relative positions of the head and bed members controlling movement of the toggles from the first mentioned side of dead center to the last mentioned side thereof, and resilient means arranged to give as the toggles pass dead center.

7. A pressing machine comprising head and bed members, at least one of which is movable, operating mechanism for the movable member, and control means for said mechanism, including spaced manuals movable from inoperative to intermediate positions and thereafter to full operative positions, a whipple-tree connected with the manuals and movable to a position in which said operating mechanism is actuated, when the manuals are moved to intermediate or full operative positions, releasable and resilient means tending to maintain the whipple-tree in said mechanism actuating position, said means being actuated by movement of the manuals to full operative positions, and being releasable by movement of a manual to an inoperative position, and means governed by the relative positions of the head and bed members controlling movement of the manuals from intermediate to full operative positions.

8. A pressing machine comprising head and bed members, at least one of which is movable, operating mechanism for the movable member, and control means for said mechanism, including spaced manuals movable from inoperative to operative positions, a whipple-tree connected with the manuals and movable to a position in which said operating mechanism is actuated, when the manuals are moved to operative positions, and releasable means to maintain the whipple-tree in said mechanism actuating position, said means being actuated by movement of the manuals to full operative positions, and being releasable by movement of a manual to an inoperative position and resilient means tending to resist movement of the whipple-tree from its said actuating position.

9. A pressing machine comprising head and

bed members, at least one of which is movable, operating mechanism for the movable member, and control means for said mechanism, including spaced manuals movable from inoperative to intermediate positions and thereafter to full operative positions, a source of pressure fluid connected with said operating mechanism, a valve controlling the entire flow of said pressure fluid to said mechanism, over-center toggles respectively connected with the manuals and connected with the single valve, the toggles being at one side of dead center when the manuals are in inoperative or intermediate positions and being locked at the opposite side of dead center when the manuals are in full operative positions, and means governed by the relative positions of the head and bed members controlling movement of the toggles from the first mentioned side of dead center to the last mentioned side thereof.

10. A pressing machine comprising head and bed members, at least one of which is movable, operating mechanism for the movable member, and control means for said mechanism, including spaced manuals movable from inoperative to intermediate positions and thereafter to full operative positions, a main valve connected to control the entire flow of motive fluid to the motor, a pilot valve connected to operate the main valve, over-center toggles respectively connected with the manuals and with the pilot valve, the toggles being at one side of dead center when the manuals are in inoperative or intermediate positions and being at the opposite side of dead center when the manuals are locked in full operative positions, and means governed by the relative positions of the head and bed members controlling movement of the toggles from the first mentioned side of dead center to the last mentioned side thereof.

11. A pressing machine comprising head and bed members, at least one of which is movable, operating mechanism for the movable member, and control means for said mechanism, including spaced manuals movable from inoperative to intermediate positions and thereafter to full operative positions, the manuals having elements moving towards each other in these movements, a movable barrier disposed in the space between said elements, the single barrier being arranged to oppose movement of the elements towards each other, to prevent movement of the manuals from intermediate to full operative positions until the head and bed members are substantially in contact with each other, and means controlled by said operating mechanism thereupon moving the barrier from its said opposing position.

12. A pressing machine according to claim 3, in which the valve controlling the flow of pressure fluid to the press operating mechanism comprises an intake valve and an exhaust valve, means to maintain either the intake or exhaust valve away from its seat while the other valve is seated, and spring means tending to move the diaphragm to an inoperative position with regard to the first mentioned valve.

13. In a pressing machine of the class having spaced manuals controlling the mechanism of the machine, wherein the manuals are movable from inoperative to intermediate positions and to full operative position, and wherein means are provided for locking the manuals in full operative position, the combination with said manuals of a valve mechanism comprising an intake valve and an exhaust valve, means to maintain either one or the other of the valves away from its seat

- while the other valve is seated, and spring means tending to seat the exhaust valve, to take up wear between the exhaust valve and its respective seat.
- 5 14. In a pressing machine of the class having spaced manuals controlling the mechanism of the machine, wherein the manuals are movable from inoperative to intermediate positions and to full operative position, and wherein means are
- 10 provided for locking the manuals in full operative position, the combination with said manuals of a valve housing having connecting chambers, one chamber connecting with a source of motive fluid, the other chamber being connected to supply said motive fluid to operating mechanism of the machine, the housing having an exhaust port, and intake valve controlling the connection between the chambers, an exhaust valve controlling the exhaust port, means to maintain
- 15 either one or the other of the valves away from its seat while the other valve is seated, and spring means tending to seat the exhaust valve, to take up wear between the exhaust valve and its respective seat.
- 20 15. A pressing machine comprising head and bed members, at least one of which is movable, operating mechanism therefor, and control means for said mechanism including spaced manuals movable from an inoperative to an intermediate position and to a full operative position, the manuals being automatically maintained in the full operative position when moved thereto, stop means governed by the relative position of the head and bed members to control
- 25 the movement of the manuals from intermediate

to full operative position, a whippetree connected with the manuals and movable thereby, and valve means connected to be controlled by movement of the whippetree, when the manuals are moved from inoperative to intermediate position and to the full operative position after the stop means has been actuated and resilient means arranged to permit movement of the manuals to the full operated position.

- 5 16. A control for presses of the class having 10 a bed member and a head member movable to the bed member, comprising control means for the head member including spaced manuals movable from an inoperative to an intermediate position and to a full operative position, the manuals being automatically maintained in the full operative position when moved thereto, a whippetree connected with the manuals and movable thereby, a resilient connector pivotally mounted on the whippetree, requiring movement of both 15 ends of the whippetree to advance the connector forward, the whippetree being connected at opposite sides of the pivot with the manuals respectively, a valve operable by forward movements of the connector, movement of the manuals from the inoperative to the intermediate position effecting forward movement of the connector, a stop to prevent further movement of the manuals until the head has moved substantially to the bed, and means to withdraw the 20 stop at that time to allow movement of the manuals to full operative position.

O. H. PEARSON. 25
EDWARD PEARSON. 30 35
